CLAIM

The ornamental design for a computer console, as shown and described.

DESCRIPTION

FIG. 1 is a front perspective view of a computer console showing my new design;

FIG. 2 is a front elevational view thereof;

FIG. 3 is a left side elevational view, the right side elevational view being a mirror image thereof; and

FIG. 4 is a top plan view thereof.

The rear of the console is flat and unornamented.
